UNITED STATES PATENT OFFICE.

CLARENCE J. KLEIN, OF BELLEVUE, PENNSYLVANIA, ASSIGNOR TO UNITED ENGINEERING AND FOUNDRY COMPANY, OF PITTSBURGH, PENNSYLVANIA, A CORPORATION OF PENNSYLVANIA.

MATERIAL-HANDLING APPARATUS.

Application filed September 30, 1925. Serial No. 59,527.

The present invention relates broadly to material handling apparatus, and more particularly to apparatus of this character adaptable for use in mills and the like handling slabs, billets, strips or other shapes or bodies which it is desired to store or pile in predetermined places or piles. While the invention is particularly useful in iron and steel mills for the handling of heavy shapes, the utility of the invention is not limited in this respect.

In many cases it is desirable to transfer shapes directly from a roll table or other carrier to cradles provided for their reception, the cradles being located different distances from the carrier. In many mills it has been customary heretofore to utilize cranes, slings or similar equipment for this purpose. The manual attention required, as well as the objection to overhead equipment by reason of danger, have constituted inherent objection to such installations. The present invention has for one of its objects the provision of transfer mechanism selectively operable in the general horizontal plane of the carrier for engaging shapes on the carrier and delivering the same at will to predetermined cradles or piles at varying distances from the carrier. Specifically, therefore, the present apparatus may be referred to as a selective piler.

In the accompanying drawings there is shown for purposes of illustration only, a preferred embodiment of the present invention, it being understood that the drawings do not define the limits of my invention as changes in the construction and operation disclosed therein may be made without departing either from the spirit of the present invention or the scope of my broader claims.

In the drawings:

Figure 1 is a top plan view of one form of apparatus embodying the present invention, the drawings being largely diagrammatic for the sake of clearness;

Figure 2 is a side elevational view, partly in section, of the construction illustrated in Figure 1, the parts being shown reversed side for side as viewed in the drawings;

Figure 3 is a view similar to Figure 2, of a part only of the installation, these parts being shown on an enlarged scale and partly in section;

Figure 4 is a transverse sectional view on an enlarged scale on the line IV—IV of Figure 3 looking in the direction of the arrows;

Figure 5 is a view similar to Figure 3 illustrating on still larger scale the dog carriage and drag;

Figure 6 is a transverse sectional view on the line VI—VI of Figure 5 looking in the direction of the arrows, and

Figure 7 is a partial sectional view on the line VII—VII of Figure 5 illustrating the drag.

In carrying out the present invention there may be provided a carrier 2 illustrated herein as comprising a roll table having a line shaft 3 for driving the rolls thereof in the direction and at the speed desired. Disposed at one side of the carrier is a series of stands 4 constructed to form cradles A, B, C and D respectively at different predetermined distances from the carrier, and into which it is desired to selectively pile bodies from the carrier. Each of the cradles may have cushioning means 5 therein formed by blocks of wood or other suitable material.

On the side of the carrier opposite the cradles are supports 6 carrying spaced angles 7 constituting elongated guides for slides 8, there being a series of supports and a pair of guides for each slide. Each slide is preferably constructed of side angles 9 connected at their upper edges by a channel beam 10, the sides of the channel extending between and definitely spacing the angles. Movably mounted for limited sliding movement within each of the slides is a rack bar 11 having its teeth projecting downwardly through the bottom of its slides between the side angles 9.

Adjacent the inner ends of the guides 7, there is secured to each pair of guides a drag, each comprising a yoke 12 extending around and below the guides and projecting upwardly beyond the edges thereof. Extending transversely above the slides, and bearing at their undersides against the channels 10 are shoes 13 held downwardly against the slides by springs 14 carried by bolts 15 having nuts 16 by means of which the pressure on the springs may be varied at will. The ends of the shoes 13 preferably extend between lugs 18 formed on the upstanding ends of the yokes 12 and projecting

upwardly therefrom, thereby holding the shoes against endwise movement and preventing twisting thereof. The shoes act as drags on the respective slides tending to initially hold the same against movement until such time as the drive thereon becomes positive, and thereby effective for overcoming the friction of the shoes.

Secured to the inner end of each of the rack bars 11 is a dog-carrier 19, preferably shaped to partially interfit with its rack bar, as clearly shown in Figure 5, and bolted in position thereon. These dog carriers are generally of trough-shaped construction having their bottoms shaped to slide on the guide angles 9 of the slides, and having their openings disposed upwardly. The sides of the dog carriers are formed with elongated openings 20 adapted to receive pivot pins 21 carried by the angles 9 and extending transversely through the carriers, the angles 9 being provided with bearing plates 22 for the pins.

Loosely mounted on each of the pins 21 is a dog 23 having a tail 24 of such weight that the dogs normally tend to assume the full line position of Figures 5 and 6 as soon as they are released. From Figures 3 and 5 it will be apparent that the channels 10 of the slides terminate at a point slightly ahead of the drags, but that the side angles 9 continue forwardly to form bearings for the pivot pins 21. Projecting upwardly from the bottom of the trough of each of the dog carriers is a lug 25 having its rear end inclined and adapted to engage a projection 26 on its corresponding dog. By reason of this construction, it will be apparent that upon movement of any dog carrier to the left, as viewed in Figure 5, or from its full line position of this figure to its dotted line position, relatively to its slide, the lug 25 will engage the projection 26 on the dog and swing the dog to its dotted line position, while upon similar relative movement in the opposite direction the dog will assume its normal full line position. This relative movement continues until one end or the other of the elongated openings 20 engages their cooperating pin 21, and is insured by the holding action of the drag on the slide, permitting the rack bar to move initially relatively thereto until positive drive is transmitted through the pivot pin.

For producing the desired movement of the rack bars 11 there is provided a drive shaft 27 journaled in suitable bearings 28, and provided between each pair of bearings with a gear 29 meshing with the teeth of one of the rack bars. The drive shaft may be driven in any desired manner, as for example by means of a motor 30. In order to prevent tilting of the slides and rack bars, and disengagement of the rack bars from their driving gears, the bearings 28 are continued upwardly to accommodate rolls 31.

The relative position of the parts of the apparatus is such that with the dogs in normal or full line position they will project above the plane of delivery of the carrier, as clearly indicated by chain lines in Figures 3 and 5, and full line in Figure 2. Thus, when the shaft 27 is operated in a clockwise direction as viewed in these figures, it will be effective for simultaneously moving all of the rack bars to the right, relatively initially to the slides. Upon the commencement of this movement, the dogs will drop to their normal position ready to engage any body on the carrier. At the same time, the dog carriers will gradually move forwardly below the plane of delivery of the carrier, ready to receive and support such body when transferred from the carrier. When this relative movement has continued to an extent sufficient to bring the ends of the openings 20 into engagement with the pins, a positive drive will be transmitted to the slides, thereby moving the slides and rack bars concomitantly to the left as viewed in Figure 1, and to the right as shown in Figures 2, 3 and 5. This movement as continued will bring the dog-carriers over the respective cradles, the overhanging portions of the slides successively engaging the stands 4, and being supported thereby. When the dog-carriers are in position over the desired cradles, rotation of the drive shaft 27 will be reversed, thereby effecting an initial movement of the rack bars in the opposite direction relative to the slides. During this movement the dogs will engage the bodies on the dog-carriers and prevent movement thereof with the rack bars. Thus, gradually, the dog carriers will be withdrawn from supporting relationship to the bodies, and they will fall into the desired cradle. Continued relative movement will effect a swinging movement of the dogs to their dotted line position, whereby they are free to pass under bodies on the carrier during the return movement of the slides and rack bars. This return movement will occur just as soon as the pins are engaged by the slots and the friction of the drag thereby overcome. The operation may be repeated as often as desired and successive bodies delivered to any desired position or distance from the carrier.

The carrier may be provided with spaced guides 32 extending transversely of the carrier and adapted to support the dog carriers when in position adjacent the carrier.

The advantages of the present invention arise from the provision of means definitely positioned relatively to a carrier and operable for engaging and transferring a body from the carrier to a point any desired distance from the carrier.

Further advantages arise from the provision of an apparatus of the general nature

referred to operable for selectively delivering and piling successive bodies at any one of a plurality of selected positions.

I claim:

- 5 1. In a material handling apparatus, a carrier, a plurality of cradles at one side of said carrier and located different distances therefrom, means operable transversely of said carrier for engaging a body thereon and 10 delivering the same to any one of said cradles, said cradles being shaped to support said means when moved into cooperative relation thereto, and driving mechanism for said means, substantially as described.
- 15 2. In a material handling apparatus, a carrier, a plurality of cradles at one side of said carrier and located different distances therefrom, a slide operable transversely of said carrier for engaging a body thereon and 20 delivering the same to any one of said cradles, said cradles being shaped to support said slide when moved into cooperative relation thereto, and driving mechanism for said slide, substantially as described.
- 25 3. In a material handling apparatus, a carrier, a plurality of cradles at one side of said carrier and located different distances therefrom, a slide normally supported at one side of said carrier, means for moving said 30 slide transversely of said carrier to the opposite side thereof, said cradles being shaped to support said slide when in cooperative relation thereto, and with engaging and supporting means carried by said slide, substantially as described.
- 35 4. In a material handling apparatus, a carrier, a plurality of cradles at one side of said carrier and located different distances therefrom, a slide normally supported at one 40 side of said carrier, means for moving said slide transversely of said carrier to the opposite side thereof, said cradles being shaped to support said slide when in cooperative relation thereto, and with engaging and supporting means carried by said slide relative- 45 ly thereto, substantially as described.
5. In a material handling apparatus, a carrier, a slide supported at one side thereof, a rack bar movably carried by said slide, means for initially moving said rack bar relatively to said slide and then concomitantly with said slide, and a transfer dog carried by said rack bar and movable to inoperative position upon relative movement 50 between the rack bar and slide in one direction and movable to operative position upon such relative movement in the opposite direction, substantially as described.
6. In a material handling apparatus, a carrier, a slide supported at one side thereof, a rack bar movably carried by said slide, means for initially moving said rack bar relatively to said slide and then concomitantly with said slide, a transfer dog carried 60 by said rack bar, and means insuring such

initial relative movement, substantially as described.

7. In a material handling apparatus, a carrier, a slide supported at one side thereof, a rack bar movably carried by said slide, means for initially moving said rack bar relatively to said slide and then concomitantly with said slide, a transfer dog carried by said rack bar, and friction means co-operating with said slide for insuring such initial relative movement, substantially as described.

8. In a material handling apparatus, a carrier, a slide supported at one side thereof, a rack bar movably carried by said slide and having a lost motion connection therewith, means for initially moving said rack bar relatively to said slide and then concomitantly with said slide, and a transfer dog carried by said rack bar, substantially as described.

9. In a material handling apparatus, a carrier, a slide, a rack bar movably carried by said slide and having a lost motion connection therewith, means for initially moving said rack bar relatively to said slide and then concomitantly with said slide, and a transfer dog carried by said rack bar, substantially as described.

10. In a material handling apparatus, a carrier, a slide supported at one side thereof, a rack bar movably carried by said slide, means for initially moving said rack bar relatively to said slide and then concomitantly with said slide, a transfer dog carried by said rack bar, and a plurality of cradles on the opposite side of said carrier, said cradles being shaped to support said slide when in cooperative relation thereto, substantially as described.

11. In a material handling apparatus, a carrier, a plurality of slides supported at one side thereof, a rack bar movably carried by each of said slides, means for simultaneously initially moving all of said rack bars relatively to said slides and then concomitantly with said slides, and a transfer dog carried by each of said rack bars, substantially as described.

12. In a material handling apparatus, a carrier, a plurality of slides, a rack bar movably carried by each of said slides, means for simultaneously initially moving all of said rack bars relatively to said slides and then concomitantly with said slides, and a transfer dog carried by each of said rack bars, substantially as described.

13. In a material handling apparatus, a carrier, a plurality of slides supported at one side thereof, a rack bar movably carried by each of said slides and having a lost motion connection therewith, means for simultaneously initially moving all of said rack bars relatively to said slides and then concomitantly with said slides, and a transfer

- dog carried by each of said rack bars, substantially as described.
14. In a material handling apparatus, a carrier, a plurality of slides supported at one side thereof, a rack bar movably carried by each of said slides, means for simultaneously initially moving all of said rack bars relatively to said slides and then concomitantly with said slides, a transfer dog carried by each of said rack bars, and means insuring such initial relative movement, substantially as described.
15. In a material handling apparatus, a carrier, a plurality of slides supported at one side thereof, a rack bar movably carried by each of said slides, means for simultaneously initially moving all of said rack bars relatively to said slides and then concomitantly with said slides, a transfer dog carried by each of said rack bars, and friction means insuring such initial relative movement, substantially as described.
16. A selective piler, comprising a slide, a rack bar movably carried thereby and having a lost motion connection therewith, a dog carried by said rack bar and movable to operative and inoperative positions, and means for initially moving said rack bar relatively to said slide and then concomitantly moving said slide and rack bar, substantially as described.
17. A selective piler, comprising a slide, a rack bar movably carried thereby and having a lost motion connection therewith, a dog carried by said rack bar and movable to operative and inoperative positions, means for initially moving said rack bar relatively to said slide and then concomitantly moving said slide and rack bar, and means insuring such initial relative movement, substantially as described.
18. A selective piler, comprising a slide, a rack bar movably carried thereby and having a lost motion connection therewith, a dog carried by said rack bar and movable to operative and inoperative positions, means for initially moving said rack bar relatively to said slide and then concomitantly moving said slide and rack bar, and friction means insuring such initial relative movement, substantially as described.
19. In a material handling apparatus, a carrier, a slide supported at one side thereof, a bar movably carried by said slide, means for initially moving said bar relatively to said slide and then concomitantly with said slide, and a transfer dog carried by said bar and movable to inoperative position upon relative movement between the bar and slide in one direction and movable to operative position upon such relative movement in the opposite direction, substantially as described.
20. In a material handling apparatus, a carrier, a slide supported at one side there-
- of, a bar movably carried by said slide, means for initially moving said bar relatively to said slide and then concomitantly with said slide, a transfer dog carried by said bar, and means insuring such initial relative movement, substantially as described.
21. In a material handling apparatus, a carrier, a slide supported at one side thereof, a bar movably carried by said slide, means for initially moving said bar relatively to said slide and then concomitantly with said slide, a transfer dog carried by said bar, and friction means cooperating with said slide for insuring such initial relative movement, substantially as described.
22. In a material handling apparatus, a carrier, a slide supported at one side thereof, a bar movably carried by said slide and having a lost motion connection therewith, means for initially moving said bar relatively to said slide and then concomitantly with said slide, and a transfer dog carried by said bar, substantially as described.
23. In a material handling apparatus, a carrier, a slide, a bar movably carried by said slide and having a lost motion connection therewith, means for initially moving said bar relatively to said slide and then concomitantly with said slide, and a transfer dog carried by said bar, substantially as described.
24. In a material handling apparatus, a carrier, a slide supported at one side thereof, a bar movably carried by said slide, means for initially moving said bar relatively to said slide and then concomitantly with said slide, a transfer dog carried by said bar, and a plurality of cradles on the opposite side of said carrier, said cradles being shaped to support said slide when in operative relation thereto, substantially as described.
25. In a material handling apparatus, a carrier, a plurality of slides supported at one side thereof, a bar movably carried by each of said slides, means for simultaneously initially moving all of said bars relatively to said slides and then concomitantly with said slides, and a transfer dog carried by each of said bars, substantially as described.
26. In a material handling apparatus, a carrier, a plurality of slides, a bar movably carried by each of said slides, means for simultaneously initially moving all of said bars relatively to said slides and then concomitantly with said slides, and a transfer dog carried by each of said bars, substantially as described.
27. In a material handling apparatus, a carrier, a plurality of slides supported at one side thereof, a bar movably carried by each of said slides and having a lost motion connection therewith, means for simultaneously initially moving all of said bars rela-

- tively to said slides and then concomitantly with said slides, and a transfer dog carried by each of said bars, substantially as described.
- 5 28. In a material handling apparatus, a carrier, a plurality of slides supported at one side thereof, a bar movably carried by each of said slides, means for simultaneously initially moving all of said bars relatively to said slides and then concomitantly with said slides, a transfer dog carried by each of said bars, and means insuring such initial relative movement, substantially as described.
- 10 29. In a material handling apparatus, a carrier, a plurality of slides supported at one side thereof, a bar movably carried by each of said slides, means for simultaneously initially moving all of said bars relatively to said slides and then concomitantly with said slides, a transfer dog carried by each of said bars, and friction means insuring such initial relative movement, substantially as described.
- 15 30. A selective piler, comprising a slide, a bar movably carried thereby and having a lost motion connection therewith, a dog carried by said bar and movable to operative and inoperative positions, and means for initially moving said bar relatively to said slide and then concomitantly moving said slide and bar, substantially as described.
- 20 31. A selective piler, comprising a slide, a bar movably carried thereby and having a lost motion connection therewith, a dog carried by said bar and movable to operative and inoperative positions, means for initially moving said bar relatively to said slide and then concomitantly moving said slide and bar, and means insuring such initial relative movement, substantially as described.
- 25 32. A selective piler, comprising a slide, a bar movably carried thereby and having a lost motion connection therewith, a dog carried by said bar and movable to operative and inoperative positions, means for initially moving said bar relatively to said slide and bar, and friction means insuring such initial relative movement, substantially as described.
- 30 33. In a material handling apparatus, a carrier, a plurality of receivers at one side thereof and located at different distances therefrom, a conveying arm movable sidewise and effective for transferring material from the carrier to any one of the receivers, and means operating in a predetermined relation with the movement of the conveying arm for causing discharge of the material on the conveying arm.
- 35 34. In a material handling apparatus, a plurality of material receivers occupying different positions, a conveying arm movable in varying amounts so as to bring it to the several positions and adapted to carry material to the different receivers at such positions, and means automatically operable at the end of a conveying movement of the arm for automatically discharging the material carried thereby.
- 40 35. In a material handling apparatus, a carrier, a conveying arm adapted to bodily support and move material sidewise from the carrier, and means operating in a predetermined relation with the conveying arm and effective for engaging material thereon so as to positively discharge the same from the carrier.

In testimony whereof I have hereunto set my hand.

CLARENCE J. KLEIN.
